DESIGN FOR A FLUORESCENT LIGHT FIXTURE

Christian Hofstetter, Oxnard, Calif.

Application December 4, 1942, Serial No. 108,946

Term of patent 7 years

To all whom it may concern:

Be it known that I, Christian Hofstetter, a citizen of the United States, residing at Oxnard, in the county of Ventura and State of California, have invented a new, original, and ornamental Design for a Fluorescent Light Fixture, of which the following is a specification, reference being had to the accompanying drawing, forming a part thereof.

Figure 1 is a frontal elevational view of a

fluorescent light fixture, showing my new design.

Figure 2 is a side or edge elevational view.

The rear view of the fixture is substantially the same as the front view.

I claim:

The ornamental design for a fluorescent light fixture, as shown and described.

CHRISTIAN HOFSTETTER.
